UNITED STATES PATENT OFFICE

166,899

PAIR OF SHEARS

John Ahlbin, Fairfield, Conn.

Application June 27, 1950, Serial No. 10,773

Term of patent 14 years

(Cl. D22—5)

To all whom it may concern:

Be it known that I, John Ahlbin, a citizen of the United States, residing at Fairfield, county of Fairfield, and State of Connecticut, have invented a new, original, and ornamental Design for Pair of Shears, of which the following is a specification, reference being had to the accompanying drawing, forming part thereof.

Figure 1 is a plan view of a pair of shears showing my new design; and

Fig. 2 is a side view thereof.

I claim:

The ornamental design for a pair of shears, as shown.

JOHN AHLBIN.
